DESIGN FOR WALL-PAPER.

Design No. 12,538, dated October 18, 1881.

UNITED STATES PATENT OFFICE.

EDUARD LEISSNÈR, OF NEW YORK, N. Y., ASSIGNOR TO LEISSNÈR & LOUIS,
OF SAME PLACE.

DESIGN FOR WALL-PAPER.

SPECIFICATION forming part of Design No. 12,538, dated October 18, 1881.

Application filed August 25, 1881. Term of patent 3½ years.

To all whom it may concern:

Be it known that I, EDUARD LEISSNÈR, of New York, in the county and State of New York, have invented a new and original Design 5 for Wall-Paper and Similar Fabrics, of which the following is a specification.

This invention relates to a new and original design for wall-paper and similar fabrics; and it consists in the novel grouping and configuration of parts hereinafter more fully described.

The accompanying photograph illustrates a face view of a wall-paper bearing my new design.

A stem, B, extends lengthwise through the 15 background, at one side thereof, and carries flowers c, resembling the *flower-de-luce*, lancet-

shaped leaves g, cabbage-shaped ornaments o, and star-flowers i, k, and j. A branch, m, which projects from the stem B, carries flowers h r t. Another branch, a, which also projects from the 20 stem B, carries lily-like flowers b and e, and large open flowers f.

I claim—

The design for wall-paper, consisting of the stem B, having branches a m, leaves g, and 25 flower-like ornaments b, c, e, f, h, i, j, k, o, r, and t, substantially as shown.

EDUARD LEISSNÈR.
